UNITED STATES PATENT OFFICE.

EDWIN H. HUMPHREY, OF BATTLE CREEK, MICHIGAN, ASSIGNOR, BY DIRECT AND MESNE ASSIGNMENTS, OF THREE-FOURTHS TO LAKEWOOD CASTER CO., A CORPORATION OF NEW YORK, AND ONE-FOURTH TO THOMAS JENNINGS, OF ROCHESTER, NEW YORK.

CASTER.

No. 877,081.

Specification of Letters Patent.

Patented Jan. 21, 1908.

Application filed February 25, 1907. Serial No. 359,163.

To all whom it may concern:

Be it known that I, EDWIN H. HUMPHREY, a citizen of the United States, residing at Battle Creek, in the county of Calhoun and State of Michigan, have invented a new and useful Caster, of which the following is a specification.

This invention relates to casters or supports for bedsteads and various other articles of furniture.

When beds or other articles of furniture are manufactured, it is not usual to place the casters in position, owing to the liability of sliding or falling, especially of heavy head or foot boards, but it is necessary to employ some means in the warehouse, storerooms, and the like to support the furniture clear of the floor in order that it may be readily handled and moved about without danger of marring or mutilating the footpieces. The usual practice is to drive a small wooden peg in the opening formed in the footpiece for the subsequent reception of the caster stock or pintle, the peg having a rounded lower face, so that the articles may be moved to and fro over the floor without undue friction, the peg serving further to keep the foot pieces of the articles some distance above the surface of the floor to prevent injury. These pegs are removed when the furniture is sold, and the caster stocks are inserted in the openings. The disadvantages of this method of employing wooden pegs are the expense of the pegs and the placing of the same in position, the danger of breakage of the pegs, and consequent damage to the furniture, and the task of removing the pegs from the openings, an operation which often requires considerable time where the pegs have become jammed.

One of the principal objects of the present invention is to overcome this and other difficulties by providing a furniture supporting member in the form of a peg or projection that is permanently attached to the article of furniture, and which serves subsequently as a means for securing or connecting the caster.

A further object of the invention is to provide a device of this class which may be readily applied, and which will securely hold the caster in place.

A still further object of the invention is to provide a device of this class which may be

permanently attached to metallic bedsteads and other articles of furniture without the aid of tools, and without the employment of auxiliary fastenings, such as clamps, screws, bolts and the like.

With these and other objects in view, as will more fully hereinafter appear, the invention consists in certain novel features of construction and arrangement of parts, hereinafter fully described, illustrated in the accompanying drawings, and particularly pointed out in the appended claims, it being understood that various changes in the form, proportions, size and minor details of the structure may be made without departing from the spirit or sacrificing any of the advantages of the invention.

In the accompanying drawings:—Figure 1 is a sectional elevation of the lower portion of an article of furniture provided with a caster and caster attaching means constructed in accordance with the invention. Fig. 2 is a side elevation, showing the furniture supporting and caster attaching peg. Fig. 3 is a sectional elevation of the peg member showing the initial shape of the ring or band of compressible material which is employed to hold the same in place. Fig. 4 is a detail perspective view of the caster proper detached. Fig. 5 is a view similar to Fig. 1, illustrating the application of the invention to an article formed of wood. Fig. 6 is a similar view showing the caster removed and the peg in position.

Similar numerals of reference are employed to indicate corresponding parts throughout the several figures of the drawings.

In the drawing, A designates the lower end of a portion of a metallic bedstead or other article of furniture, and in carrying out the invention, it is merely necessary to cut the tubing off to the proper length, there being no necessity of providing screw threads, bolt openings or the like for the subsequent attachment of the caster and its holding means.

To the lower end of the tube A is connected a supporting and caster attaching peg 10, the bottom of the peg being rounded in order to reduce the surface area in frictional contact with the floor or caster socket. The

shank of the peg is cylindrical in form, and at the top is provided with a circular disk 11 on which the lower end of the tube A rests. Projecting upward from the disk is an annular flange 12 which fits within the lower portion of the tube, and surrounding this flange is a compressible ring 15 which may be formed of rubber, or other suitable material, the ring being initially plano, convex in form in cross section, as shown in Fig. 3, and its greatest external diameter being slightly larger than the internal diameter of the tube A.

When the flange and its attaching ring 15 are forced up into the tube, the material of which the attaching ring is composed is compressed, and its contour in cross section is altered to that shown in Fig. 1, so that there will be an extensive area of the ring 20 in frictional contact with the inner wall of the tube, and in practice it is found impossible to withdraw the ring and flange from place by the exertion of any strain or force to which the article of furniture may be ordinarily subjected.

After the peg has been placed in position, its lower rounded face presents a very small surface for frictional contact with the floor, so that the article of furniture may be moved 30 around from place to place without damage to the floor, and with minimum exertion. This moving of the furniture while resting on the pegs will furthermore serve to polish the lower surfaces of the pegs, so that they 35 may be in better shape to serve as bearings when the casters are subsequently attached.

The caster comprises a wheel 20 and a frame 21, the latter being provided with a pair of arms 22 carrying the axle of the wheel. 40 The frame has an opening for the reception of the lower end of a socket member 23, the lower part of the socket being approximately globular in form to receive the ball shaped end of the peg, and from thence upward being cylindrical in form to receive the shank portion of the peg. The socket member is split as shown clearly in Fig. 4, so that it may be forced readily on to the peg, and when the ball shaped lower end of 50 the peg has been received in the globular socket, the arms which comprise said socket member will move inward around the shank of the peg and prevent the caster from falling from place.

55 In order to shield the socket member from strain and prevent twisting of its parts while the bed or other object is being moved from place to place, the upper portion of said socket member is surrounded by an annular flange 25 which depends from the disk 11, and in case of any strain, the socket member is reinforced by the adjacent surface of the flange.

Where the device is applied to articles formed of wood, as shown, for instance, in Fig. 6, the shank of the peg is provided with an integral upwardly extending pin 30, the pin being barbed, as indicated in Fig. 6, so that it may be firmly locked in place by driving. The peg when introduced in this manner will form a support for the article, as shown in Fig. 6, and the caster may be readily attached in the same manner as previously described, and as illustrated in Fig. 5.

When the caster is placed in position, the principal weight of the article of furniture is transmitted through that portion of the surface of the peg which was previously in contact with the floor, and if this surface has become polished through friction, the caster 80 may turn more freely than if unpolished, so that the shifting of the furniture from place to place on the supporting pegs is rather advantageous than otherwise.

I claim:—

85 1. In caster attaching devices for furniture, a pair of members, one provided with a peg having a rounded end, and the other provided with a split socket for the reception of the peg, the peg carrying member having a reinforcing flange snugly embracing the open end of the socket and serving to prevent spreading of the same.

2. In caster attaching devices for furniture, a pair of members, one of said members 95 having a peg, the body of which is cylindrical, the peg terminating in an enlarged spherical head, the other of said members having a split socket arranged to receive both the spherical and cylindrical portions of 100 the peg, the peg carrying member being provided with a flange that surrounds the open end of the socket and serves to reinforce and prevent spreading of said socket.

3. A furniture supporting peg having a 105 cylindrical body portion, and a spherical end, and provided with a disk having a downwardly extending flange spaced from the spherical body of the peg, and a caster having a split socket receiving the peg and fitting 110 partly within said flange, the latter serving to prevent spreading of the socket.

4. A caster attaching device, comprising a disk arranged to receive the weight of the article of furniture and provided at the top 115 with a vertically disposed annular flange of less diameter than the disk, a band of compressible material surrounding the flange, and a peg depending from the flange and provided with an enlarged rounded head for 120 the reception of the socket of the caster member.

5. A caster attaching device comprising a disk arranged to receive the weight of the article of furniture, a peg depending from 125 the disk and provided with an enlarged

rounded head, a flange also depending from the lower surface of the disk, the flange being spaced from and concentric with the peg, in combination with a caster having a split 5 socket for the reception of the peg, the flange serving to receive the split end of the socket and reinforce the same.

In testimony that I claim the foregoing as my own, I have hereto affixed my signature in the presence of two witnesses.

EDWIN H. HUMPHREY.
